UNITED STATES PATENT OFFICE.

WENZL LÜTZ, OF CSEPEL, NEAR BUDAPEST, HUNGARY, ASSIGNOR OF ONE-HALF TO
JOHN LUTZ, OF CHICAGO, ILLINOIS.

FURNACE.

Application filed September 6, 1921. Serial No. 498,789.

To all whom it may concern:

Be it known that I, WENZL LÜTZ, a citizen of Czecho-Slovakia, residing at Csepel, near Budapest, Hungary, have invented certain new and useful Improvements in Furnaces, of which the following is a specification.

This invention relates to furnaces, and has for its object means for preventing over-heating especially for too long a time, of the bricks of the oven of the furnace, especially those located near the entrance of the fuel to the furnace, where the gas and air are mixed and combined by combustion. In general the means which I provide for accomplishing this purpose consists of a special form of head for introducing the air and gas into the furnace, and also for conveying the burned gases out of the furnace; 10 similar heads being positioned at each end of the furnace, and each being supplied with means for alternately passing fuel to the furnace or passing the burned gases away from the furnace. By this arrangement, while one head is supplying fuel at one end of the furnace, the other head is passing the burned gases to the recuperator or chimney from the other end of the furnace. When the bricks at the combustion 15 end of the furnace are becoming overheated the heads are reversed so that the cooler burned gases pass out at the heated end and the cooler end becomes temporarily the combustion chamber. By thus reversing 20 the position and function of the heads as often as may be necessary, perhaps every thirty minutes, the temperature of the bricks surrounding the combustion end of the furnace is maintained lower and injury 25 thereto is materially reduced.

Of the drawings Fig. 1 shows a Martin furnace according to the invention, in cross section; and Fig. 2 is a plan view of the same with one end thereof in section.

In the drawings *a* and *b* are respectively the gas and air flues which are inclined towards the furnace *c* and arranged to produce a suitable flame; *d* is a flue for conveying the burned gases to the chimney, and it is 45 built in the same head *g* as the fuel flue. When reversing the direction of the flow of gases the head is moved sideways on wheels *e*, and in place of the fuel flues the waste gas flue is placed in front of the combustion 50 chamber *f*. In this manner, by suitable ar-

rangements, the fire-bricks in the neighborhood of the combustion chamber are alternately heated by the hot gases as the air and fuel gas are combined, and cooled by the cooler burned gases as they pass out at that 60 end of the furnace; and it will be the same with the fire-bricks adjacent the other end of the furnace. The idle flues are kept from cooling off by suitable walls, gates, and so forth; and means may be introduced to heat 65 the idle flues, such as a gas flame.

The two heads may be moved across the ends of the furnace simultaneously, so as to alternately supply fuel to the furnace and receive burned gases from the furnace, by 70 the use of any suitable mechanism, electrically or mechanically, or by the use of the cylinders *h* suitably supplied with compressed air.

Any suitable means may be provided for 75 properly controlling the gas passageways when the heads are moved. I prefer for the purpose to provide flues *i* and *j* which are adapted to register with the passageways *a* and *b* respectively, when the air and gas 80 is being supplied, and which register with the passageways *d* when the burned gases are to be removed. The flues *i* from each end of the furnace are operatively connected with a four-way valve casing *k* which is operatively connected with the chimney *l* and with a pipe *m*, the pipe *m* being operatively connected with any suitable source of gas supply. The casing *k* is provided with a rotatable valve *n* which is adapted to close the 85 gas supply to one head and to open it to the other when the heads are shifted, and at the same time to correspondingly open and close the chimney flue. Similarly the flues *j* are connected with a four-way valve casing *o* 90 which is also operatively connected to the chimney and to a pipe *p* which is operatively connected to any suitable source of air supply. This casing is also provided with a rotatable valve *q* which is so set as to allow 95 air to pass to the left-hand head when it is desired and at the same time to allow the burned gases to pass from the other head and to reverse this process. Any suitable means may be used for rotating the valves 100 when the heads are shifted.

In order to more satisfactorily carry out my invention I provide, between the furnace and each head, plates *r* and *s*. The plate *r* is fixed to its head, and has openings *t* there- 110

in which register respectively with the passageways *a*, *b*, and *d* in the head. The plates *s* are fixed to the ends of the oven and each has an opening *u* registering with the oven opening, and hence which registers with the opening *t*, of the corresponding head, which is in operative position. By the use of these plates the leakage of gas and injury to the adjacent portions of the head and furnace 10 may be materially reduced. Flanges *v* on the plates *s* limit the movement of the heads.

The plate *s* also closes the openings *t* which are not in operative position, and thus reduces the cooling tendency of the interior 15 surfaces of the passageways which are not operating.

In order to still further reduce the cooling of the unused passageways I provide openings *w* in the plate *s* which are arranged to 20 be operatively connected to suitable sources of supply of air and combustible gas, which, when the passageways are in idle position, produce a flame therein which maintains the required temperature of the walls of the 25 passageways. The arrangement of the plates and openings is such that the passageways *w* are closed by the plates *r* when the passageways are not registering with the idle openings *t* in the plates *r*.

30 Any suitable means may be used for keeping the edges of the openings *t* and *u* from becoming overheated, such as by passing water or steam through the chambers *x* surrounding the openings. The valves *n* and *q* 35 are operated automatically as the head *g* is shifted by means of an arm *a'*, links *b'*, and the gear-wheels *c'*; the arm being fixed to one wheel, and the wheels meshing and being fixed respectively to the valves. It is to be 40 understood that the drawings are more or less diagrammatic.

I claim as my invention:

1. A furnace having an opening therein, a head movably mounted adjacent said opening, said head having two passageways therethrough, one end of one of said passageways registering with said opening when the head is in one position, and one end of the other passageway registering with said 45 opening when the head is in another position, and means for heating each of said passageway ends when the other end is registering with said opening.

2. A furnace having an opening therein, 50 a head movably mounted adjacent said opening, said head having two passageways

therethrough, one end of one of said passageways registering with said opening when the head is in one position, and one end of the other passageway registering with said opening when the head is in another position; and a plate between said head and said furnace, said plate having an opening therethrough registering with the opening in said furnace, and said plate extending from said 55 furnace beyond the position of the non-registering passageway in said head.

3. A furnace having an opening therein, a head movably mounted adjacent said opening, said head having two passageways 70 therethrough, one end of one of said passageways registering with said opening when the head is in one position, and one end of the other passageway registering with said opening when the head is in another position; and a plate between said head and said furnace, said plate having an opening therethrough registering with the opening in said furnace, and said plate extending from said furnace beyond the position of the non-registering passageway in said head; and means for passing combustible gas through said plate and into the non-registering passageway. 80

4. A furnace and a head operatively connected with each end of said furnace, each head having a fuel passageway and a waste gas passageway therethrough, a flue connecting the two heads, each head arranged to be moved transversely of said furnace so as to alternately register the said passageways with said furnace and with said flue, and a four-way valve in said flue, said valve adapted to be operatively connected with a chimney and with means for supplying fuel. 85

5. A furnace and a head operatively connected with each end of said furnace, each head having a fuel passageway and a waste gas passageway therethrough, a flue connecting the two heads, each head arranged 100 to be moved transversely of said furnace so as to alternately register the said passageways with said furnace and with said flue, and a four-way valve in said flue, said valve adapted to be operatively connected with a chimney and with means for supplying fuel; 105 and means for automatically operating said valve as one of said heads is moved.

In testimony whereof, I hereunto set my hand:

WENZL LÜTZ.
